UNITED STATES PATENT OFFICE.

BERT JACOBS, OF LA CROSSE, WISCONSIN.

DOOR-SECURING MEANS.

Application filed June 12, 1924. Serial No. 719,682.

To all whom it may concern:

Be it known that I, BERT JACOBS, a citizen of the United States, residing at La Crosse, in the county of La Crosse and State 5 of Wisconsin, have invented certain new and useful Improvements in Door-Securing Means; and I do hereby declare the following to be a full, clear, and exact description of the invention, such as will enable others 10 skilled in the art to which it appertains to make and use the same.

Banks and analogous institutions where large sums of money are kept and readily accessible for the transaction of business 15 and to which the general public has free access are frequently held up during business hours and robbed, the robbers usually escaping because the entrance is unobstructed.

20 In accordance with the present invention the building or other place to be safeguarded is provided with a doorway which serves both for the entrance and the exit, all other openings being guarded to prevent exit 25 thereby. A revolving door controls this doorway and must be turned to permit the passage of a person through the door opening. The present invention provides means whereby the door may be held from rotating 30 thereby preventing ingress to or egress from the building, said means being controllable from various points and when actuated in an emergency operating to prevent the escape of a hold-up or suspect and insuring a capture. 35

Other objects and advantages will be apparent and suggest themselves as the nature of the invention is understood.

40 While the drawings illustrate an embodiment of the invention it is to be understood that in adapting the same to meet different conditions and requirements, various changes in the form, proportion and minor details of construction may be resorted to without departing from the spirit of the invention.

45 Referring to the accompanying drawings forming a part of the application:

Figure 1 is a diagrammatic view showing the application of the invention,

50 Figure 2 is a horizontal section on the line 2-2 of Figure 3,

Figure 3 is a vertical transverse sectional view on the line 3-3 of Figure 2, showing more clearly the relation of the parts,

55 Figure 4 is a top plan view showing the parts on a larger scale,

Figure 5 is an enlarged sectional detail view.

Figure 6 is a detail sectional view on the line 6-6 of Figure 5,

Figure 7 is a detail view of the switch,

Figure 8 is an enlarged sectional view of the mounting for the brake operating screw, and

Figure 9 is a detail sectional view on the line 9-9 of Figure 8.

Corresponding and like parts are referred to in the following description and designated in the several views of the drawings by like reference characters.

The numeral 1 designates a doorway whereby ingress and egress is effected and said doorway is controlled by means of a revolving door 2 which normally closes and obstructs the doorway and which must be turned to admit of a person passing through the doorway in either direction, both when entering the building or place or when leaving the same. A brake drum 3 is fast to the post 4 and a brake member 5 is in cooperative position with the brake drum to grip the same and prevent rotation of the door and thereby prevent anyone from passing through the doorway either in an attempt to enter the building or to leave the same. Thus in the event of an attempt to burglarize the bank or other institution, the door securing means may be set, thereby preventing rotation of the door and the escape of the thief or suspect whose capture may thus be effected.

In the preferred construction, the brake member 5 consists of a band which encircles the drum 3 and which is made fast at one end, as indicated at 6, the opposite end 95 being extended outwardly and provided with a threaded opening to receive a screw 7 which is mounted in bearings 8. A pulley 9 or like element is fast to the screw 7 and is connected to a corresponding element 10 so 100 as to rotate therewith. The elements 9 and 10 are shown as pulleys and are connected by means of a drive belt 11. An electric motor 12 has the pulley 10 fast to its shaft and when the motor is in operation, the 105 screw 7 is rotated so as to contract the brake band 5 and grip the drum 3 and thereby prevent rotation of the door 2.

The electric motor 12 is included in a circuit 15 which is controlled by means of a switch 13 which is normally closed, it being understood that the circuit including the

motor 12 includes a number of switches 14 which are conveniently disposed to be operated from determinate points so that upon closing any one of the switches, the motor circuit is closed and the motor caused to operate so as to set the brake and when the brake has been set, the switch 13 is operated, thereby automatically breaking the circuit and stopping the motor. To this end the switch may be of the form detailed in Figure 7. Upon reference thereto, the terminals to which the wires of circuit 15 are fastened are indicated at 21 and 22, mounted on and insulated from the casing 23 of such switch, pivotally connected to the terminal 21 is a movable switch arm 24 adapted to engage a switch arm 25 in conducting relation to terminal 22. Arm 24 carries a plunger 26 insulated therefrom and movable through a relatively large opening 27 in casing 23. As a result of this construction, when the band 5 is applied, the terminal arm 5^a thereof will strike against the plunger 26 and thus swing the switch arm 24 out of contact with the arm 25, thus breaking the electric circuit through the motor 12. Continued movement of said plunger 26 causes it to engage a conductor arm 28 and a projection 29 carried by plunger 26 and insulated from arm 24, to engage a terminal 30. Thus a circuit is completed through wires 31 to an audible signal 32, the latter circuit receiving the current from a battery 33. Thus after the motor has ceased and the door is locked, the bell 32 will ring and continue to ring until the parts are restored to normal position. By providing the motor circuit with a number of switches said circuit may be closed from any one of a number of points, thereby effecting operation of the door securing means whereby to prevent the escape of a robber or suspect in an attempted hold-up or other emergency.

To prevent binding of the screw 7 it is threaded into a slide 16 mounted in a guide 45 17 bolted or otherwise attached to a part of the frame 18. The guide 17 is channelled and receives the slide 16 which is held in place by a keeper 19. A pair of pins 20 projecting from the slide 16 receive an end 50 portion of the brake band 5 as shown most clearly in Figure 4.

What is claimed is:

1. Means for safeguarding a bank or other place containing valuables, the same consisting of a revolving door, a brake mechanism for holding the door against rotation, operating means for setting the brake mechanism, the same including an electric motor and a circuit therefor containing switches 55 located at determinate points so that operation of any one of the switches effects an operation of the motor and a setting of the brake mechanism to secure the door, and a circuit-breaking switch adapted to be automatically operated by the brake after the latter has been set, whereby to break the circuit and stop the motor.

2. Means for safeguarding a bank or other place containing valuables, the same 70 consisting of a revolving door, a brake mechanism including a brake drum and a brake band, a screw having threaded engagement with the brake band, an electric motor included in a circuit containing switches 75 disposed at determinate points, connecting means between the motor and screw, and a circuit-breaking switch adapted to be operated by the brake mechanism after the latter has been set to effect a stopping of the motor.

In testimony whereof I affix my signature in the presence of two witnesses.

BERT JACOBS.
